TRACK-TAMPING ASSEMBLY

BACKGROUND AND SUMMARY OF THE INVENTION

The present invention relates to a machine for tamping ballast underneath a track including rails supported on a plurality of ties resting on the ballast and spaced in the direction of track elongation, and more particularly to improvements in the lubrication of the moving parts of track-tamping assemblies mounted on such machines. Machines of this type include means for movably mounting the tamping tools and drive means for pivoting, vibrating and vertically moving the tamping tools.

This invention is useful in connection with the known type of track tamping assemblies which include a pair of opposed tamping tools and means mounted on a vertically adjustably mounted tamping tool carrier for vibrating and reciprocating the opposed tamping tools in the direction of track elongation. Each tool has two ends, and the lower end is arranged for immersion in the ballast adjacent one of the ties, with the one tie positioned between the opposed tools of the pair. The invention is very advantageously applied to the known type of twin track tamping assemblies which include two such pairs of opposed tamping tools, the pairs of tools being so spaced from each other in the direction of track elongation that the tools of each pair which are adjacent to each other are at a smaller distance from each other than the distance between adjacent ties whereby the adjacent tools of the two pairs of tools may be immersed in the ballast between two adjacent ties. With either type of track tamping assembly, a common vibrating means may be provided for all tamping tools, as shown, for instance, in our U.S. Pats. Nos. 3,357,366 and 3,429,276.

These known assemblies form a unit, at least to a certain extent, because the drives for the tools are coordinated. Also, a series of transversely arranged tools is associated with each rail, and all the associated tools move with one pair which is driven. Therefore, the invention is described only in connection with the one, driven pair in any series of pairs of tools which are transversely aligned.

While these known track-tamping assemblies have advanced far in the direction of compact construction, it is the primary object of the present invention further to advance in this direction and to unite all parts of the track-tamping assembly into one well lubricated unit requiring a minimum of space.

This and other objects are accomplished in accordance with this invention by providing a common lubricating system which includes a housing defining a common sump for lubricating medium for the tamping tools. The housing encloses at least some, and preferably all, the mounting and/or drive means for the tamping tools.

Such a common lubricating system very effectively contributes to a rational mounting and combination of all moving parts of the track-tamping assembly, and to provide an effective tamping unit. It is quite useful with a variety of tamping tool assembly types.

In one preferred embodiment, a twin track-tamping assembly for each track rail is mounted in a common housing and the two housings are supplied from a common lubricating medium source. However, it is also possible to mount two separate single or twin-track tamping assemblies spaced in the direction of track elongation on a track tamper, such assemblies being movable in relation to each other and each assembly being enclosed in a common housing, and all housings being supplied from a common lubricating medium source.

The common lubricating system may include a common source of lubricating medium and a circulating system including a pump, an oil-conditioning device including an oil filter and/or cooling system, a conduit for delivering the reconditioned oil from the device to the housings of the track-tamping assemblies and/or to all the lubricating points thereof, a sump in the housings whence the used oil is returned through a con-

duit to the pump which delivers the oil to the conditioning device for reuse.

In a preferred embodiment, the housing defining the lubricating medium sump constitutes the vertically adjustable carrier for the track-tamping assembly. This housing may enclose only the pivotal mountings of the tamping tools immersed in the sump, or it may enclose all moving parts of the assembly. While the pivotal mountings for the tamping tools are immersed in the oil sump, a centrally supplied oil conduit system delivers oil to other points of the assembly which require lubrication, such conduits including, if desired, oil spray nozzles, baffles and other oil-distributing devices properly guiding the oil to the lubrication points. DETAILED DESCRIPTION OF DRAWING

15 The above and other objects, advantages and features of the present invention will become more apparent from the following detailed description of some preferred embodiments, taken in conjunction with the accompanying drawing wherein

20 FIGS. 1 to 3 are schematic side views of three different types of generally conventional ballast tamping and track-leveling machines wherein this invention may be used to advantage;

25 FIG. 4 is a vertical section along line IV-IV of FIG. 7 of a mounting of a twin-tamping tool assembly according to one embodiment of the invention;

30 FIG. 5 and 6 are schematic views showing two additional embodiments of tamping tool mountings according to the invention;

35 FIG. 7 is an enlarged end view of a pair of transversely aligned tamping tool assemblies, taken in the direction of arrow VII of FIG. 4; and

40 FIGS. 8 and 9 are schematic top views illustrating the positions of the tamping tool assemblies in the machines of FIGS. 2 and 3, respectively.

DETAILED DESCRIPTION

To avoid redundancy, like parts operating in a like manner have been designated by the same reference numerals in

45 FIGS. 1 to 3. Track-tamping and leveling machines of such general types are well known and are described, for instance, in our U.S. Pats. Nos. 3,192,870, 3,211,109, 3,357,366 and application Ser. No. 668,266, filed July 25, 1967, now U.S.

50 Pat. No. 3,494,297. They include a carriage frame 1 having front and rear wheels 2, 2 mounted for movement on track 3 whose rails are supported on a plurality of ties 4 resting on the ballast (not shown) and spaced in the direction of track elongation. Referring more specifically to FIG. 1, a carrier 5 is vertically adjustably mounted on the carriage frame and a track-tamping assembly comprising a pair of opposed tamping tools 6 is mounted on the carrier for vertical movement therewith. The tamping tools are vibratory and reciprocable in the direction of track elongation.

55 As indicated in FIGS. 1 to 3, present-day track tampers also include means for grading or leveling the track, including a track-lifting means 9 at the front end of the overhanging portion of the carriage frame, and a reference system in respect of which the track is leveled, this system including a reference

60 line 10 extending from a front bogie 11 in the uncorrected track section to a rear station 12 resting on the corrected track section. The reference system also includes a stop 13 (and 13' in FIG. 3) cooperating with the reference line and resting on the track section being tamped by each track tamping assembly. All of this structure and its function are well known.

65 As is conventional, a separate tamping tool assembly, each consisting of a series of pairs of associated opposed tamping tools, is mounted on a carrier vertically above each rail of the track. According to the present invention, a common or central lubricating medium supply source 7 is connected by a lubricating medium supply conduit system to all lubricating points of the tamping tool assemblies so that all assemblies have a common lubricating system although each assembly is enclosed in a housing defining a common sump for the lubricating medium for each assembly.

In the embodiment of FIG. 2, each tamping tool assembly includes a series of two pairs of opposed tamping tools, and the pairs of tools are so spaced from each other in the direction of track elongation that the tools of each pair which are adjacent to each other are at smaller distance from each other than the distance between adjacent ties whereby the adjacent tools of the two pairs may be immersed in the ballast between the adjacent ties.

If each assembly associated with a respective track rail is housed in a separate carrier 5', the two housings are again connected to the same lubricating medium supply 7 (see also FIG. 8). However, it is also possible to mount the assemblies for both rails in a single housing.

In the track tamping and leveling machine of FIG. 3, two twin units 5' are mounted for movement in relation to each other along the direction of track elongation. In this embodiment, the carriage frame 1' is of bridgelike configuration and runs on swivel trucks 2', 2' supporting a respective end of the carriage frame. A support frame 14 for the tamping tool assemblies is supported on the carriage frame intermediate its ends and has guide rails on which the tamping tool assembly carriers are mounted for movement in the direction of track elongation. The track-lifting means 9 is mounted at the front end of the support frame and, if laterally movable, may also serve for track lining. A hydraulic jack 15 engages the track rails between the two twin track tamping assemblies in the center of the support frame 14 and, if the machine also serves as a track liner, this jack may be laterally movable to serve for lining the track at this point. However, jack 15 serves primarily to press downwardly against the track and thus to prevent unwanted upward movement of the track at this point and thus to maintain the track in the graded position. As will appear from the top view of FIG. 9, four separately housed twin track tamping assemblies of this type may still be centrally supplied from a common lubricating medium source 7.

A preferred mounting for a twin-tamping tool assembly is shown in FIG. 4. In this embodiment, the tamping tool assembly carrier is constituted by a common housing 16 defining a sump for a lubricating medium, such as oil. The housing 16 is vertically adjustably mounted on columns 17, 17 in the carriage frame 1 or 1' for moving the lower ends of the tamping tools into and out of immersion in the ballast.

Each tamping tool of the twin tamping tool assembly is shown to include a pivot 19 intermediate its ends about which the tool is reciprocated in the direction of the track elongation, the tool being a lever swinging about this pivotal mounting. An upper portion 21 of the tamping tools extends from pivotal mounting 19 into housing 16 and a lower portion 18' extends downwardly from the pivotal mounting and outwardly of the housing. The lower portion 18' of the tamping tools constitutes a mount for tamping tool jaw 18.

The housing 16 has a bottom formed with concave portions 20 accommodating respective pivots 19 of the tamping tools which are flooded with lubricating oil. Suitable sealing means constituted by gaskets 19' are provided around the tamping tool pivots for preventing leakage of oil through the housing bottom. The upper and lower tamping tool portions are detachably connected by means of a bolt 22 extending transversely to the axis of the tool, as best seen in FIG. 7, a sealing gasket 23 being interposed between the forked upper end of the lower tamping tool portion 18' and the lower end of the upper tamping tool portion 21 fitting into the forked upper end of the lower tool portion. In this clamping arrangement, the relative angle of the tamping tool portions in respect of each other may be readily adjusted while the gasket 23 remains in place so that the distance between the lower ends of the tools of each pair may be changed, for instance to tamp double ties.

As is best seen in FIG. 7, each housing 16 consists of 70 detachably connected wall portions 16', 16'', which may be bolted together along their mating flanges so that the housing may be opened for access to the parts mounted therein, the shafts or pivotal mountings for the moving parts in the housing being supported in the housing wall. The subdivision of the

housing into two or more wall portions thus makes it possible readily to replace individual parts in the housing by removing one of the wall portions temporarily.

In the illustrated embodiment of the housing, the housing for the track-tamping assembly associated with a respective one of the track rails comprises a center portion 16" and two lateral portions 16', 16'' detachably fastened to the center portion along flanges extending in vertical planes parallel to the direction of track elongation so that the lateral wall portions 10 may be selectively removed for access to the interior of the housing. Suitable sealing means or gaskets extend between the flanges of the housing portions so that the wall of the housing will be sealed against oil leakage in the assembled condition. FIG. 7 also shows the pulley and belt drive 38 for driving cam shaft 24 which serves as a common tamping tool vibrating means for all the tamping tools.

The cam shaft is journaled in the housing wall and extends in a plane which is transverse and vertical to the track, and runs centrally between columns 17, 17 on which the housing and tamping tool carrier is mounted for vertical movement. A pair of arms 25, 25 extend oppositely from the cam shaft in the direction of track elongation, and the arms are vibrated by the shaft upon rotation thereof by drive 38. The upper ends of the 15 tamping tools of each pair are linked to a respective cam shaft arm in the manner now to be as is it being noted that in the illustrated embodiment, and as is conventional, a series of four as of tamping tools are associated with each rail for tamping each tie on both sides of the rail.

20 Separate drives 26 and 27 are connected to the upper ends of each tamping tool of a pair (the three associated pairs being mounted on the same shafts and, therefore, being driven therewith). The drives reciprocate the opposed tamping tools in the direction of track elongation, the illustrated drives being hydraulic motors. A transmission element 28 is mounted in the housing 16, which holds all the shafts and pivotal 25 mountings of the track-tamping assembly, the fulcrum 29 of the transmission element being mounted on the housing wall independently of the camshaft. The upper ends of the tamping tools of each pair are linked to a respective transmission element 28 by means of interposed drives 26, 27, and each transmission element is at least indirectly connected to the vibrating means, being linked to the outer ends of the camshaft arms in the illustrated embodiment.

30 As shown, the transmission element is advantageously a lever having two arms, a bell crank lever being illustrated in FIG. 4. The upper end of one of the tamping tools of each pair is linked to one lever arm via hydraulic motor 26, and the upper end of the other tamping tool of the pair is linked to the lever arm via hydraulic motor 27. In this manner, each pair of 35 opposed tamping tools is associated with one common transmission element, the structure being identically duplicated for each pair of the twin-tamping tool assembly (the three associated pairs moving in unison with the driven pair).

The two arms of the transmission lever 28 extend at an angle to each other, which angle faces the vertical plane wherein the camshaft axis extends, and the upper transmission lever arm is connected to the associated vibrating arm 25. The fulcrum 29 of the transmission lever is positioned below a horizontal plane defined by the camshaft axis in the embodiment of FIG. 4. The upper end of the tamping tool farther removed from the camshaft is linked to the arm of the transmission lever extending upwardly from fulcrum 29, and the upper end of the tamping tool closer to camshaft 24 is to the arm of the transmission lever extending downwardly from fulcrum 29. In this manner, the tamping tools of each pair are vibrated in opposite directions.

The length of the reciprocating stroke of the opposed tamping tools of each pair may be further varied by providing adjustable stops 30 for the reciprocating movement of the outer tool of each pair. For this purpose, a fixed stop may be mounted on the cylinder of hydraulic motor 26 and a movable stop 30 for selective engagement therewith may be mounted 75 so as to be movable into the path of the cylinder movement by

a hydraulic motor or like drive 31. The movable stop 30 will engage the fixed stop and thus limit further movement when the stop 30 is swung into the path of the cylinder movement of hydraulic motor 26 by drive 31. As mentioned before, the distance between the opposed tools of each pair is further adjustable by changing the angle between the upper and lower portions of the tools.

In the schematically illustrated embodiment of FIG. 5, like parts functioning in a like manner are designated by like reference numerals. In this embodiment, the housing 16 encloses only a part of the tamping tool assembly, i.e. only the pivots 19 of the tamping tools are immersed in a lubricating medium sump in the housing. The lubricating points of the other pivotal mountings and drives for the tamping tools 6 are supplied from a common or central supply of lubricating medium 7 by a lubricating medium conduit system 32.

In this embodiment, the kinematic system for connecting the upper tamping tool ends to the camshaft arms 25 also differs from that of FIG. 4, the transmission element 28' being a straight two-armed lever one of whose arms is connected to the camshaft arm at the same point as the drive 26' while the other transmission lever arm is connected to drive 27' of the opposing tamping tool.

In the embodiment of FIG. 6, the linkage system of FIG. 5 is combined with the housing system of FIG. 4, i.e. all the pivotal mountings, shafts, etc. of the tamping tool assembly are fully enclosed within the housing. Furthermore, this embodiment differs from those hereinbefore described by a circulating lubricating medium system. In this system, the lubricating conduit system 34 includes a pump 33 which delivers lubricating medium to a device 35 for conditioning the medium, such as an oil filter and/or an oil-cooling system. The reconditioned oil is then delivered into housing 16 and to the various lubricating points of the track-tamping assembly, and leaves the sump at the bottom of the housing by gravity through an outlet whence the used lubricating medium is returned into the conduit system by pump 33. In this manner, the oil may be used for an extended period of time without being changed.

FIG. 6 also shows some preferred delivery means for the lubricating medium to lubricate assembly points positioned outside the sump, such as spray nozzles 36, oil distributing baffles 37, which may simply be cast ribs in the housing wall, etc., all of which serve adequately to provide lubrication for all moving parts of the assembly within the housing.

While such oil distributing means are of particular advantage in an enclosed housing, they may also find use in an arrangement similar to that of FIG. 5 where the sprayed or other distributed oil may then be further directed into the sump in the housing therebelow whence it may be recirculated in a similar manner as described in connection with FIG. 6.

With twin track-tamping assemblies, it will be most useful to enclose all moving parts of the assemblies, including the vibrating and the reciprocating means for the tamping tools within a common housing, such as shown in FIGS. 4 and 7. However, the present invention is also useful with simple track-tamping assemblies, such as indicated in FIG. 1, as well as the multiple tampers illustrated in FIG. 3.

The kinematics of the tamping tool drives have been illustrated in connection with various embodiments to indicate some possibilities of compactly assembling all parts in a common housing. Modifications and variations of the exemplified systems will readily occur to those skilled in the art without departing from the spirit and scope of the present invention.

We claim:

1. A machine for tamping ballast underneath a track including two rails supported on a plurality of ties resting on the ballast and spaced in the direction of track elongation, said machine comprising a pair of track-tamping assemblies each including two pairs of opposed movable tamping tools, each tool having two ends and one of the ends of the tamping tools being arranged for immersion in the ballast adjacent one of the ties, with said one tie being positioned between the tools, and said pairs of tools being spaced from each other in the

direction of track elongation so that the tools of each pair which are adjacent to each other are at a smaller distance from each other than the distance between adjacent ones of said ties whereby said adjacent tools of the two pairs may be immersed in the ballast between said adjacent ties; means for movably mounting the tamping tools; and drive means for pivoting, vibrating and vertically moving the tamping tools; and the machine further comprising the improvement of a common lubricating system which includes a pair of interconnected housings, each housing being associated with a respective one of the track rails, at least partially enclosing a respective one of the track-tamping assemblies and at least a portion of at least one of said means for mounting and driving the tamping tools, and defining a common sump for lubricating medium for the tamping tools; and the two housings being in transverse alignment.

2. The machine of claim 1, comprising two pairs of said housings, one of the pairs being spaced from the other pair of housings in the direction of track elongation and said pairs being movable in relation to each other in said direction, a common lubricating system interconnecting all of said housings.

3. The machine of claim 1, wherein the common lubricating system comprises a central device for preparing and supplying the lubricating medium for said housings.

4. The machine of claim 1, wherein each housing constitutes a vertically adjustably mounted carrier for the tamping tools, the pivotal mountings of the tamping tools are immersed in said common sump, and a centrally supplied lubricating medium conduit system directs the medium to lubricating points of the mounting and drive means of the tamping tools which are positioned above the sump.

5. The machine of claim 4, wherein each housing encloses the vibrating and drive means of the tamping tools.

6. The machine of claim 5, wherein the vibrating means is common to both pairs of opposed tamping tools in each of said housings, a drive is connected to each one of the other ends of the tamping tools of said pairs for reciprocating the respective tamping tools in the direction of track elongation, and a transmission lever having two arms is interposed between the vibrating means and the drives of the opposed tools of each pair, one of the lever arms being linked to the drives and the other lever arm being at least indirectly connected to the common vibrating means for vibrating the tools of each pair in opposite directions.

7. A machine for tamping ballast underneath a track including rails supported on a plurality of ties resting on the ballast and spaced in the direction of track elongation said machine comprising a track tamping assembly including movable tamping tools, means for movably mounting the tamping tools, and drive means for pivoting, vibrating and vertically moving the tamping tools, and the machine further comprising the improvement of a common lubricating system which includes a housing defining a common sump for lubricating medium for the tamping tools, the housing enclosing at least a portion of at least one of the said means for mounting and driving the tamping tools, and consisting of detachably interconnected wall portions, and any shafts for tamping tool assembly parts mounted in the housing for movement about said shafts are journaled in said housing wall portions.

8. The machine of claim 7, wherein the housing consists of three of said portions each extending in the direction of track elongation and separated by vertical planes parallel to said direction, the two lateral housing portions being detachably connected to the central housing portion.

9. A machine for tamping ballast underneath a track including rails supported on a plurality of ties resting on the ballast and spaced in the direction of track elongation, said machine comprising a track tamping assembly including movable tamping tools, means for movably mounting the tamping tools, and drive means for pivoting, vibrating and vertically moving the tamping tools, and the machine further comprising the improvement of a common lubricating system which includes a

housing defining a common sump for lubricating medium for the tamping tools, the housing enclosing at least a portion of at least one of the said means for mounting and driving the tamping tools, and including a bottom, pivotal mountings for the tamping tools are immersed in said common sump at the bottom of the housing, and sealing means is provided around the pivotal mountings to prevent leakage of the lubricating medium through the bottom.

10. The machine of claim 9, wherein the housing bottom defines downwardly directed concave portions housing the

pivotal mountings of the tamping tools.

11. The machine of claim 9, wherein each tamping tool comprises an upper portion extending from the pivot into the housing and a lower portion extending downwardly from the pivotal mounting and outwardly of the housing, the lower portion constituting a mount for a tamping tool jaw, the lower portion of the tamping tool has a forked upper end grasping the lower end of the upper tamping tool portion, and a bolt detachably fastening the last-named ends together.
